UNITED STATES PATENT OFFICE.

JOS. ANGER AND JOS. PRESTELE, OF NEW YORK, N. Y.

IMPROVEMENT IN SEWING-MACHINES.

Specification forming part of Letters Patent No. 43,890, dated August 23, 1864.

To all whom it may concern:

Be it known that we, JOSEPH ANGER and JOSEPH PRESTELE, both of the city, county, and State of New York, have invented certain new and useful Improvements in Sewing-Machines; and we do hereby declare that the following is a full, clear, and exact description of the same, reference being had to the accompanying drawings, forming a part of this specification, in which—

Figure 1 represents a vertical longitudinal section of our invention. Fig. 2 is a rear elevation of the same. Fig. 3 is a transverse vertical section of the same, taken in the plane indicated by the line $x\ x$, Fig. 1. Fig. 4 is a detached sectional view of the cam-shaft and parts connected therewith.

Similar letters of reference in the several figures denote like parts.

The object of our invention is to construct and arrange the several parts of a sewing-machine in such a manner that the same, however rapidly operated, will work comparatively noiseless and perfectly sure.

The invention consists, first, in the employment or use of a disk of untanned leather or rawhide toothed, so as to mesh with the ordinary driving-gear of a sewing-machine in such a manner that a rapid motion from said driving-gear can be transmitted to the main shaft of the sewing-machine without causing the least noise, and at the same time a durable gear is provided; second, in the arrangement of one or more adjustable friction-rollers at the lower end of the cam-lever which imparts motion to the needle, in combination with a curved projecting rim that forms the cam, in such a manner that said friction-rollers can be kept in close contact with the sides of the projecting rim or cam, thereby producing a sure and noiseless motion of the cam-lever; third, in the peculiar construction and arrangement of the feed-motion, consisting of a feed-wheel provided with a flange extending near its periphery parallel to the axis, and a toggle-lever made to vibrate upon the axis, in combination with a toggle-piece and jaw-piece placed inside of the flange in the wheel and provided with bearing-points outside of a radial line, in such a manner that by moving the lever in one direction the bearing-points are brought nearer to a radial line, thereby causing the toggle-piece to bind firmly between the rim of the feed-wheel

and the lever, and forcing the feed-wheel to partake of the motion of said lever, whereas by moving the lever in the opposite direction the toggle-piece is relieved and the feed-wheel remains stationary.

To enable others skilled in the art to make and use our invention, we will proceed to describe it with reference to the drawings.

A represents the frame of the machine, provided with bearings $a\ a$, in which the cam-shaft B is made to revolve. Firmly secured to one end of this shaft is the small gear-wheel C, which is constructed of two metal disks, $c\ c$, and a disk, c' , made of untanned leather or rawhide, the said disk c' being secured between the disks $c\ c$ and provided with cogs, as shown in Figs. 2 and 4, to gear into the ordinary large driving-gear, D, which is mounted on an adjustable stud, a^* , in the frame A, and through which motion is imparted to the working parts of the machine. The cam-shaft B also bears the cam E, which is cast with a projecting rim, e , curved, so as to produce the required motion for looping the needle-thread. The motion is transmitted from the cam E to the needle-slide by means of the lever F, and that end of this lever which is in contact with the cam or rim e is provided with two friction-rollers, $p\ p$, made of rawhide or other suitable material, one being permanently secured upon the cam-lever F and arranged to be in contact with one side of the rim e , and the other being placed upon a stud, i , made to slide in a slot, k , formed in the end of the lever, and provided with a set-screw, l , whereby the friction-rollers can always be kept in close contact with the sides of the rim e , as clearly shown in Figs. 1 and 4. The feed-wheel R, which has a flange, r , on its side, near to its periphery, rotates on a stud, M, attached in the usual way to the frame A. To the inside of the flange r a jaw-piece, N, is fitted, and motion is imparted to the feed-wheel R by the feed-lever S, that vibrates upon the stud M, and which is provided with a knife-edge projection, o , opposite the jaw-piece N. From the projection o a toggle-piece, u , extends to a cavity, n , in the jaw-piece N, being situated so that its direction deviates somewhat from the radial line drawn through the center of the feed-wheel and the cavity n . One end of the feed-lever, which extends below the stud M, is provided with a pin, to which the usual connect-

ing-link is attached, and it receives a vibrating motion in the ordinary manner by means of an eccentric upon the cam-shaft and rock-shaft. From the feed-lever S a projection rises above the stud M, opposite to the end of the jaw-piece N, and a set-screw passing through said projection works against the jaw-piece, whereby the latter can be set off from the lever and made to bear closely against the inner side of the flange of the feed-wheel. A spring, g, placed between a raised portion of the frame A and the feed-lever, tends to press the feed-lever off from the jaw-piece and prevents the shake which, with ordinary machines, occurs when the pin of the feed-lever has worked loose in the connecting-link.

From the foregoing description it is evident that the friction-rollers *p p* can be set at any time, so as to be in close contact with the cam E, thereby transmitting the motion of said cam at all times perfectly accurate and without noise, even when rapidly operated; and, furthermore, by the particular arrangement of our

feed-motion the stitches are made perfectly regular and of any desired length.

What we claim as new, and desire to secure by Letters Patent, is—

1. The employment or use of a toothed disk, *c*, of untanned leather or rawhide, and meshing with the ordinary driving-gear, D, of a sewing-machine, as and for the purpose described.

2. The arrangement of the adjustable friction-rollers *p p'* upon the cam-lever F, in combination with the projecting rim *e* of the cam E, constructed and operating substantially in the manner and for the purpose herein specified.

3. The arrangement of the adjustable jaw-piece N and toggle-piece *u*, in combination with the feed-lever S and feed-wheel R, constructed and operating substantially as and for the purpose set forth.

JOSEPH ANGER.

JOSEPH PRESTELE.
